Application September 30, 1952, Serial No. 312,342

2 Claims. (Cl. 101—48)

This invention relates to printing or addressing machines of the type employing changeable address-bearing elements, especially stencils, and, as illustrated herein, relates more particularly to an addressing machine arranged to apply addresses successively to different portions of a strip comprising many connected portions when the address-bearing elements are fed into successive printing positions.

Magazine and periodical publishers, manufacturers of consumers' goods and other mercantile establishments oftentimes maintain a mailing list of customers to whom literature or other material is forwarded by mail at regular intervals of time depending on the particular case. Ordinarily this requires the typing out of the addresses on each label for each customer receiving material at a particular time. This arrangement has proven unsatisfactory since the time and labor consumed in preparing the address labels make the maintenance of a mailing list an expensive operation. The past difficulties in preparing labels for a mailing list are eliminated by use of the machine of the present invention which permits a mailing list to be kept up to date by merely inserting or removing a stencil address card in the mailing list file. When it is desired to prepare the address labels, the stencil cards are fed into the machine of this invention and the addresses are printed on different portions of a continuous strip which is fed into successive printing positions. The continuous strip upon which the addresses are printed is frequently called a Dick strip.

One object of the present invention is to provide an addressing machine which will provide an address label with an address.

A further object of the invention is an improved form of mechanism for printing names and addresses on a continuous strip at high speeds.

Other objects of the invention will be pointed out in the following description and claims and illustrated in the accompanying drawings, which disclose, by way of examples, the principle of the invention and the best mode, which has been contemplated, of applying that principle.

In the drawings:

Fig. 1 is a side elevation of a printing machine illustrating the preferred embodiment of this invention.

Fig. 2 is a sectional view taken along lines 2—2 of Fig. 1.

Fig. 3 is a transverse sectional view taken along the lines 3—3 of Fig. 2.

Fig. 4 is a perspective view illustrating the construction of printing station and the mechanisms which advance the continuous strip through the station.

Fig. 5 is a detailed sectional view illustrating the position of the mechanisms for advancing the continuous strip at various periods of the strip feeding operation.

Figs. 6a and 6b show specimen stencil and continuous strip upon which printing has been effected, respectively.

Fig. 7 is a timing diagram which can be followed to

2

understand the various operations of mechanisms shown herein.

Briefly, the addressing machine of this invention has a continuous strip feeding mechanism, a holder for a stack of printing devices, preferably stencils, a printing mechanism comprising a platen roll and a print roll, a feeding mechanism for moving the printing devices from the holder into successive printing positions between the platen roll and print roll, and mechanism cooperating with the strip feeding mechanism to regulate the advance of the continuous strip through the printing position.

The machine shown herein as embodying the present invention includes a table 10 supported at the top of a conventional frame structure (not shown). A stencil holder 11 is located at the left hand end of the table 10 and extends upwardly therefrom (see Figs. 1 and 3). The successive lowermost stencils 12 of the stack 13 are moved from the stack by means of a pair of reciprocatory pushers 14 of usual construction. Each pusher 14 has connected thereto a rack member 15 which transmits motion to pusher 14 as explained hereinafter. A continuous strip of material or Dick strip 16, preferably paper, is fed from the left and passes through the printing station to be expelled from the machine on the right hand side.

Framework

Referring to Figs. 1, 2 and 3 of the drawings, the main framework comprises the heavy oblong table 10 supported by four legs (not shown) secured to the table. Two frame castings 17 and 18 are secured to the top surface of table 10 along the side edges and hereinafter will be referred to as side frames. A frame casting 19 is also secured to the top surface of table 10 between side frames 17 and 18 and will hereinafter be termed a lower middle frame. A cross bar 20 extends between side frames 17 and 18 above lower middle frame 19 and supports an upper middle frame member 21. A plate 22 is secured on one end to upper middle frame 21 and extends outwardly from it toward side frame 17. A small frame casting 23 extends upwardly from the free end of plate 22 to form a housing for the ink transfer rolls as explained hereinafter. An end plate 23 (Fig. 3) is secured to side frames 17 and 18 at the right hand end of the machine and extends at right angles to the planes of the side frames. A pair of frame castings 24 and 25 (Fig. 3) extend between the side frames 17 and 18. The lower portion of frame casting 24 is provided with an opening through which strip 16 passes on its path to the printing station. Frame casting 25 serves as the front partition of stencil holder 11, the stencils being fed from holder 11 beneath the lower end of frame casting 25 to the printing station.

The framework mounted on table 10 described above supports the printing, stencil feeding and continuous strip feeding devices.

The legs attached to the table 10 support a small sub-frame 26 shown in Fig. 1 on which is mounted the driving motor M. The other usual appurtenances of an electrically driven machine are also wholly or partly supported by this sub-frame.

Main driving mechanism

The power or driving mechanism used to operate the printing, stencil feeding and continuous strip feeding devices consists of electric motor M (Fig. 1), suitably mounted on sub-frame 26 as described above. Motor M is provided with a small pulley 27, around which is drawn an endless belt 28. Secured to a drive shaft 29 is a drive pulley 30, around which the endless belt 28 is passed. Motor M drives shaft 29 through endless belt

28 and the shaft in turn drives the mechanisms which perform the various machine operations mentioned above.

Referring again to Figs. 1 and 2, it is seen that a platen 31 is rigidly mounted on a shaft 32 and a print drum 33 is similarly mounted on a shaft 34. Shafts 32 and 33 are mounted for rotation in side frames 17 and 18. A gear 35 is fixed to a portion of shaft 32 which extends through side frame 18 and meshes with a spur gear 36 fixed to a portion of shaft 34 projecting through side frame 18. A train of gearing extends from drive shaft 29 across side frame 18 to reach the drive connections for the platen 31 and print drum 33. A gear 37 is fixed on drive shaft 29 outside side frame 18. Gear 37 engages an idler gear 38 freely mounted on a stud 39 projecting from side frame 18. Idler 38 is in mesh with a small idler gear 40 which in turn engages gear 35 to drive platen shaft 32. Idler gear 40 and a gear 44 are fastened together and freely mounted on a stud 45 extending from side frame 18. Gear 35 drives print drum shaft 34 through spur gear 36.

An inking roller 41 (Fig. 2) is driven from the same train of gears that operates the platen 31 and print cylinder 33. It is already explained that gear 36 is driven by the speed reduction gearing connected to the motor M. Inking roller 41 is mounted on a shaft 42 which in turn is rotatably mounted in upper middle frame 21 and side frame 18. Shaft 42 extends beyond side frame 18 and has a gear 43 fixed to the end thereof. Gear 36 meshes with gear 43 to drive inking roller shaft 42. The mechanism for making the inking roller effective is described hereinafter.

Stencil feeding mechanism

The stencil pushers 14 (Figs. 1 and 3) are of well known construction having the usual picker knife 14a and are guided for reciprocatory movement by suitable guides. Each pusher rack 15 is provided with rack teeth meshing with gear segments 45 secured to a shaft 46 journaled in side frames 17 and 18, there being two pushers 14, two racks 15, two segments 45 and one shaft for moving the stencils 12 from holder 11. The usual adjustable throat knife 47 and throat block are provided to prevent feeding more than one stencil at a time from holder 11. In order to keep the stencils 12 flat in the holder 11, the latter are provided with the usual follower weight 160 (Fig. 3). The shaft 46 is oscillated at regular intervals to push one stencil 12 from the holder 11 to the right in Fig. 3 into position to be gripped by feed rollers to be described later.

The stencil pushers 14 are reciprocated through a drive connection with the main driving mechanism. Drive shaft 29 is provided with a positive drive cam 48 (Fig. 1) secured thereto outside of side frame 18. An L-shaped cam follower 49 is fastened to a portion of shaft 46 projecting through side frame 18. Rotatably mounted at the extremity of each leg of follower 49 is a cam engaging roller 50. Cam 48 is so shaped as to be securely grasped between the legs of follower 49 which transmits a positive rocking motion to shaft 46. The oscillation of shaft 46 causes gear segments 45 to transmit a reciprocatory motion to racks 15 which in turn move pushers 14. The machine timing is such that the pushers 14 are reciprocated once each machine cycle of operation.

First group of stencil card feed rollers

A group of stencil feed rollers comprising two sets is provided for receiving the stencils 12 from the pushers 14 and advancing them to the printing station. These feed rollers are designated 51 and are secured on feed roller shafts 52, 53, 54 and 55 (Figs. 1 and 3) which are mounted for rotation in fixed bearings in side frames 17 and 18. Gears 56 and 57 are fastened to shafts 52 and 53, respectively, and, similarly, gears 58 and 59 are fastened to shafts 54 and 55, respectively. Idler gear 40 is rotated through the main gear train described above

carrying attached gear 44 with it. Gear 44 meshes with gears 56 and 58 to drive feed roller shafts 52 and 54 in a clockwise direction, as viewed in Fig. 1, which in turn drive feed roller shafts 53 and 55 counterclockwise through intermeshed gears 56, 57 and 58, 59. After the stencils 12 are removed from holder 11 by pushers 14, feed rollers 51 carry the stencils at an even speed to the right in Fig. 3 to a position between platen 31 and print drum 33 at the printing station.

The printing station

The print drum 33 (Fig. 3) has four ink pads 60 secured to the periphery thereof and spaced at an appreciable distance one from the other. Referring now to Fig. 6a, it is seen that stencil card 12 is composed of bonded sheets of stiff material which constitute a frame 12a having a window 12b through which the working area of the stencil 12c is exposed. This working area is subjected to pressure by a type or stylus in a manner so that the porous base of the stencil is not punctured. This preparation for printing is called "cutting" the stencil and characters and numerals representing a name and address are thus cut in each stencil to be used in this machine. The wide spacing of ink pads 60 on print drum 33 is provided because of the width of the stencil cards 12 which follow each other closely but must not lap, one on the other. It is therefore apparent that an interval of time must be allowed to permit the window portion 12b of each stencil card to arrive at the printing position. This condition also makes it necessary to retard the movement of the continuous strip 16 after each printing as explained hereinafter in connection with the strip feeding mechanism.

Print drum 33 and platen 31 are geared together as previously explained (Fig. 1) and the machine timing is such that the window 12b of a stencil card 12 starts to pass the printing position when an ink pad 60 approaches the printing position. The stencil card is tightly squeezed between the drum 33 and platen 31 causing ink to transfer through the cut portions of stencil 12c to the strip 16 upon which printing is effected.

Print drum inking mechanism

Mechanism is also provided at the printing station for inking the ink pads 60. Referring again to Figs. 2 and 3, it is seen that the inking mechanism consists of a series of ink transfer rollers, a vibrating ink transfer roller, an ink pickup roller, an ink reservoir, an inking roller, devices for operating the vibrating transfer roller and a device for controlling the amount of ink delivered by the ink pickup roller. Ink transfer rollers 61, 62 and 63 are secured on shafts 64, 65 and 66, respectively, which are mounted for rotation in upper middle frame 21 and small frame casting 23. Shaft 66 is mounted in fixed bearings but shafts 64 and 65 are mounted in vertical slots 161 and 167 respectively located in frames 21 and 23 to permit vertical adjustability of shafts 64 and 65. An ink pickup roller 68 is secured on a shaft 90 which also is rotatably mounted in frames 21 and 23. Positioned between pickup roller 68 and ink transfer roller 63 is the vibrating ink transfer roller 69.

Vibrating roller 69 (Fig. 3) is secured on a rod 70 which is rotatably mounted on a pair of support arms 71. The support arms in turn are secured to a shaft 73 having fixed bearings in upper middle frame 21 and small frame casting 23. A link member 74 is fastened to a portion of shaft 73 projecting through frame 21. Pivotedly mounted to link 74 at 75 is another link member 76 with a bifurcated lower extremity having legs 76a and 76b. A cam follower 77 is pivotally mounted on a stud 78 extending from frame 21 and carries a lug 79 which is adapted to slide in a slot 76c formed by legs 76a and 76b of the bifurcated extremity of link 76. A coil spring 80 extends between upper middle frame 21

and link 76 to pull the link downwardly to a position where lug 79 rides in slot 77c as shown in Fig. 3. Another coil spring 81 is fastened between frame 21 and cam follower 77 to continually urge the cam follower in a clockwise direction, as viewed in Fig. 3, and into constant engagement with a radial cam 82 fastened to shaft 34 between side frame 18 and frame 21.

Upon rotation of shaft 34 the rise of cam 82 causes follower 77 to rock in a counterclockwise direction about stud 78 against the pressure of springs 80 and 81, as viewed in Fig. 3, once each machine cycle. The rotation of follower 77 causes link 76 to be moved upwardly, thereby turning shaft 73 in a counterclockwise direction. The shaft 73 in turn moves support arms 71 downwardly until roller 69 is in contact with the ink pickup roller 68. As follower 77 leaves the high point of cam 82, spring 81 effects a clockwise rotation of follower 77 and link 76 is again pulled downwardly by spring 80, thereby turning shaft 73 in a clockwise direction. Support arms 71 are again moved upwardly to bring roller 69 into contact with ink transfer roller 63.

A pawl 83 (Figs. 2, 3) is pivotally connected to cam follower 77 at 84 and biased by a wire spring 85 toward engagement with the teeth of a ratchet wheel 86 secured to a portion of pickup roller shaft 90 projecting through frame 21. When cam follower 77 is rotated in a counterclockwise direction by cam 82, pawl 83 moves ink pickup roller 68 clockwise through engagement with ratchet wheel 86. Plate 22 (Fig. 1) is formed with upwardly extending side walls 22a which form a receptacle for holding ink. Roller 68 is positioned so that a portion of its periphery is always below the level of the ink contained within side walls 22a of plate 22. The rotation of roller 68 causes ink to be constantly replaced on the surface of the roller. The vibrating roller 69 removes ink from roller 68 and deposits it on ink transfer roller 63.

The ink transfer rollers are driven through a train of gears connected to gear 43 which drives the inking roller shaft 42. A gear 87 is fastened to shaft 42 near frame 21 (Fig. 2). Gears 88, 89 and 91 are fastened on shafts 64, 65 and 66 near frame 21. Gear 87 is in mesh with gear 88 to move it in a counterclockwise direction. Gear 88 in turn meshes with gear 89 which is in engagement with gear 91 to move shaft 66 in a counterclockwise direction. It is thus seen that the ink transfer rollers 61, 62 and 63 are continuously driven during machine operation to receive ink from vibrating roller 69 and carry it to the inking roller 41. The ink is transferred to each ink pad 60 as it passes roller 41, thereby insuring a steady flow of ink from the ink receptacle to the printing station.

A manually operable control lever 92 (Fig. 3) is loosely mounted on shaft 90 outside frame 21. Lever 92 is L-shaped in configuration, the short leg of which has a flange portion 92a which is adapted to engage pawl 83 and the long leg of which forms a handle for manipulation and has an arcuate slot 92b cut therein. The flange 92a is settable to cam out the point of pawl 83 altogether or at various points during the return stroke and thus limit the amount of feed of the ink roller 68. A set screw 93 is passed through slot 92b of lever 92 and is seated in a boss 94 (Fig. 2) projecting from frame 21. Lever 92 may be moved to any one of a series of positions limited only by the ends of arcuate slot 92a and is frictionally held in place at any point between the ends of slot 92a by a tightening of set screw 93. The amount of rotation of ink pickup roll 68 is determined by the number of teeth on ratchet wheel 86 advanced by pawl 83. When lever 92 is rocked to the furthest limit in a counterclockwise direction, as viewed in Fig. 3, pawl 83 is permitted to move ratchet wheel 86 through the maximum rotation. However, if lever 92 is rocked to the furthest limit in a clockwise direction, the flange portion 92a of lever 92 intercepts

pawl 83 at a point where pawl 83 is entirely disengaged from ratchet wheel 86. The machine operator can of course position lever 92 through set screw 93 at various positions between the ends of slot 92a to permit rotation of the ratchet wheel 86. In this way the amount of ink delivered to the vibrating roller 69 is regulated.

Third set of stencil card feed rollers and card guides

After a stencil card 12 is discharged from the printing station, it is drawn between a third set of feed rollers located to the right of the printing station in Fig. 1 which carry the stencil cards to a stencil stacking pocket 94. The third set of feed rollers are designated 95 and are secured on feed roller shafts 96 and 97 (Figs. 1 and 3) which are mounted for rotation in fixed bearings in side frames 17 and 18. Gears 98 and 99 are fastened to shafts 96 and 97 respectively and are intermeshed to constantly rotate rollers 95. An idler gear 100 and a gear 101 are fastened together and are freely mounted on a stud 102 extending from side frame 18. Idler 100 is driven by gear 35 which is rotated through the main gear train previously described and carries attached gear 101 with it when it is rotated. Gear 101 meshes with gear 98 to drive feed roller shaft 96 in a clockwise direction, as viewed in Fig. 1, and in turn feed roller shaft 97 is driven counterclockwise through intermeshed gears 98 and 99.

A shaft 103 (Fig. 3) is rotatably mounted in side frames 17 and 18 and carries an arm 104 fastened thereto which is approximately the same length as the stencil cards 12. A gear 105 (Fig. 1) is secured to shaft 103 outside frame 18. An idler gear 106 is loosely mounted on a stud 107 projecting from frame 18. Idler 106 is driven by idler 101 and is in mesh with gear 105 to drive shaft 103 in a counterclockwise direction as viewed in Fig. 1. The machine timing is such that arm 104 is rotated to meet the trailing edge of each stencil card 12 advanced by rollers 95 and push it into position in stacking pocket 94.

Four pairs of guides comprising upper and lower guide strips designated 72 and 108 respectively (Figs. 1 and 3) are provided to define the path of the stencil cards 12 in their movement from the stencil holder 11 through the printing station to the stacking pocket 94. Strips 72 are supported by cross bar 20, being secured thereto by screws 109. Similarly, strips 108 are supported by end plate 23, being secured thereto by screws 110. Referring now to Fig. 2, it is shown that both ends and the body of a stencil card 12 are supported and guided by the four pairs of strips while passing through the machine.

The strip feeding mechanism

The wide spacing of the ink pads 60 on print drum 33 requires that the movement of the strip 16 be retarded after each printing in order to maintain a close spacing of the printed matter as shown in Fig. 6b. This condition makes necessary a movement of the Dick strip which is accomplished by a duo of sets of oscillating rollers illustrated in Fig. 4.

A reel 111 covered with a roll of continuous Dick strip 16 is placed in the lower left hand end of the machine as shown in Figs. 1 and 3. Reel 111 is carried by a shaft 160 which is mounted in slots 112 cut in side frames 17 and 18. The strip 16 passes through an opening 24a in frame casting 24 to a position between a set of feed rollers 113. A guide roller 114 is rotatably mounted on a rod 115 which extends from lower middle frames 19. The strip 16 passes under roller 114 which rotates through frictional engagement with the strip and defines the path of the strip toward feed rollers 113. The feed rollers 113 are secured on shafts 116 and 117 which are mounted for rotation in lower middle frame 19 and side frame 17. Gears 118 and 119 (Fig. 5) are fastened to shafts 116 and 117 respectively inside frame 19 and are intermeshed to constantly rotate rollers 113.

A gear 120 (Fig. 1) is fastened to a portion of shaft 116 which projects through frame 19. Secured to platen shaft 32 is a spur gear 121 (Fig. 2) which meshes with an idler gear 122 rotatably mounted on a stud 123 extending from frame 19. Idler 122 is in mesh with another idler gear 161 (Fig. 1) loosely mounted on a stud 162 on frame 19. Idler 161 in turn engages a small idler gear 124 which is freely mounted on a stud 125 projecting from frame 19. Idler 124 meshes with gear 120 to drive shaft 116 at constant speed in a clockwise direction, as viewed in Fig. 1. Shaft 117 in turn is driven counterclockwise through intermeshed gears 118 and 119.

A second set of feed rollers 130 (Figs. 2 and 3) are driven in like manner from spur gear 121. Gears 126 and 127 (Fig. 2) are fastened to shafts 128 and 129 respectively inside frame 19 and are intermeshed to constantly rotate rollers 130. A gear 131 is fastened to a portion of shaft 129 which projects through frame 19. Idler gear 161 is also in mesh with gear 131 to drive shaft 129 in a counterclockwise direction, as viewed in Fig. 1, and in turn feed roller shaft 128 is driven clockwise through intermeshed gears 126 and 127 (Fig. 3).

The strip regulating mechanism

After strip 16 leaves feed rollers 113, it passes through a set of oscillating rollers designated 132 and 133 (Fig. 3) which are freely mounted on rods 134 and 135 respectively (Fig. 5). The oscillating rollers 132 and 133 are shown in perspective in Fig. 4, and it is seen that these rollers are housed in brackets 137 and 138, each of which is fastened to a flat portion on a shaft 140 mounted for rotation in side frame 18 and lower middle frame 19. Each bracket 137 and 138 has an overturned ear 137a and 138a respectively between which rods 134 and 135 are supported.

Referring now to Fig. 5, strip 16 is passed over rollers 132 and under rollers 133 on its path to the printing station where it travels between platen 31 and print drum 33. After leaving the printing station, strip 16 is passed through a second set of oscillating rollers designated 141 and 142 (Fig. 3) which are freely mounted on rods 143 and 144 respectively. Rollers 141 and 142 are housed in brackets 146 and 147, each of which is fastened to a flat portion on a shaft 148 mounted for rotation in frames 18 and 19. Each bracket 146 and 147 has an overturned ear 146a and 147a respectively between which rods 143 and 144 are supported. When strip 16 leaves the printing station, it is passed under rollers 141 and over rollers 142 and continues in its path to a position between feed rollers 130 which expel the printed strip 16 from the machine.

The mechanism for making oscillating rollers 132, 133 and 141, 142 effective is located on the outside of side frame 18 (Fig. 1) and is operated by a cam 149 fastened to the portion of shaft 29 projecting through frame 18. This mechanism is shown in perspective in Fig. 4 where the relationship between the operating mechanism and the oscillating rollers can be clearly seen. A cam follower 150 having a cam engaging roller 151 is freely mounted on a stud 152 extending from frame 18. An arm 157 is fastened to follower 150 and a connecting rod 153 is loosely connected to arm 157 at 154. Rod 153 pivotally engages a pair of operating arms 155 and 156 which are fastened to shafts 140 and 148 respectively outside frame 18. A wire spring 158 biases follower 150 toward cam 149 to maintain roller 151 in constant engagement with cam 149. The cam 149 is so proportioned that arms 155 and 156 constantly rock shafts 140 and 148 during machine operation, as described hereinafter in connection with the timing diagram.

Operation and machine timing

The timing diagram of Fig. 7 covers one card cycle or one cycle of Dick strip movement. The horizontal component of the chart is taken directly from left to right as the magazine feed rollers and print drum appear in the

machine. The vertical component of distance of travel is taken with respect to the movement of a stencil card 12 out of the magazine 11.

The top field, designated stencil card motion, shows the travel of a stencil card 12 through the printing station at a constant velocity of three and three hundred and eighty-four thousandths inches per card cycle. The ink pad 60 on print drum 33 contacts the card from 225° to 315° to effect printing on the Dick strip 16.

In the second field, designated Dick strip motion, the average speed of the Dick strip 16 is one and thirteen thousandths inches per card cycle and is shown by the straight dotted line. This speed is determined by the feed rollers which rotate at a constant velocity to feed strip 16 in and out of the machine. The solid line indicates the velocity of that section of Dick strip which passes over the platen 31 at the printing station to receive printing thereon. It is noted that the Dick strip 16 travels at the same velocity as the card 12 from 200° to 340° to allow the strip 16 and card 12 to pass through the printing station at the same rate of speed. This variation from the average velocity of the Dick strip is caused by the motion of oscillating rollers 132, 133 and 141, 142.

The oscillating rollers 132, 133 and 141, 142 are shown in their neutral position in Fig. 5 under the designation N. In the third field of the timing chart (Fig. 7) the angular displacement of the oscillating rollers from their neutral position is shown by the solid line. From 0° to 180° of the card cycle, the oscillating rollers are rotating counterclockwise, as viewed in Fig. 5, to the full counterclockwise position designated A. This action by the oscillating rollers stores up a quantity of strip 16 in rollers 132 and 133 in preparation for the fast printing run. At 180° the oscillating rollers rotate clockwise until 360° of the cycle where the full clockwise position is attained, as shown in Fig. 5 and designated B. The oscillating rollers are never stationary but always rotating either clockwise or counterclockwise to apply tension to the strip 16. The neutral position is only attained while the oscillating rollers are moving from the full counterclockwise position to the full clockwise position.

It is thus seen that the oscillating rollers 132, 133 and 141, 142 cause the Dick strip 16 to move opposite to the regular feed advance between 0° and 180° (Fig. 7). In Fig. 5 at A, the amount of Dick strip which is retarded is shown between the dotted lines and designated Dick strip drag. At 180° the oscillating rollers begin their clockwise rotation to permit the Dick strip 16 to advance at the same speed as the card 12 from 200° to 340°. In Fig. 5 at B, the amount of Dick strip which is released to allow rapid advance is shown between the dotted lines and designated Dick strip lag.

While there have been shown and described and pointed out the fundamental novel features of the invention as applied to a preferred embodiment, it will be understood that various omissions and substitutions and changes in the form and details of the device illustrated and in its operation may be made by those skilled in the art, without departing from the spirit of the invention. It is the intention, therefore, to be limited only as indicated by the scope of the following claims.

What is claimed is:

1. In a printing machine, a printing station comprising a print drum and a cooperating platen, means for feeding a series of stencils thereto, means for feeding a continuous strip to and from said printing station at speeds less than the rate of advance of said stencils, a first set of rollers for applying tension to said strip before and after the printing operation, a second set of rollers for applying tension to said strip during the printing operation, means for mounting each set of rollers in a manner which enables it to move in an arc about a separate fixed point, means for continuously oscillating each set of rollers to

describe a series of arcs about their respective fixed points, whereby said first set of rollers applies tension to said strip in response to arcuate movement of both sets of rollers in one direction before and after the printing operation to retard the advance of said strip and said second set of rollers applies tension to said strip in response to arcuate movement of both sets of rollers in the opposite direction during the printing operation to hasten the advance of said strip to equal the speed of a stencil.

2. In a cyclically operable printing machine, a printing station comprising a print drum and a cooperating platen, means for feeding a series of stencils thereto, means for feeding a continuous strip to and from said printing station at speeds less than the rate of advance of said stencils, a first set of rollers for applying tension to said strip during one half of a cycle and before and after the printing operation, a second set of rollers for applying tension to said strip on the other half of said cycle and during the printing operation, means for mounting each set of rollers in a manner which enables it to move in an arc about a fixed point, means for continuously moving each set of rollers to describe a series of arcs about their respective fixed points, whereby said first set of rollers applies tension to said strip in response to arcuate movement of both sets of rollers in

one direction before and after the printing operation to retard the advance of said strip and said second set of rollers applies tension to said strip in response to arcuate movement of both sets of rollers in the opposite direction during the printing operation to hasten the advance of said strip to equal the speed of a stencil.
